UNITED STATES PATENT OFFICE.

ISAAC B. MAHON, OF MARION, OHIO.

IMPROVEMENT IN CULTIVATORS.

Specification forming part of Letters Patent No. 38,593, dated May 19, 1863.

To all whom it may concern:

Be it known that I, ISAAC B. MAHON, of Marion, in the county of Marion and State of Ohio, have invented a new and Improved Cultivator; and I do hereby declare that the following is a full and exact description thereof, reference being had to the accompanying drawings, making part of this specification—

Figure 1 being a view in perspective of the entire cultivator; Fig. 2, a central vertical section of the lower end of one of the bar-shanks and of a tooth attached, showing the manner of attaching the tooth; Fig. 3, a front view of a similar part detached.

Like letters designate corresponding parts in all of the figures.

The general object of my improvements, and which they combine to accomplish in a better manner than heretofore, is the production of a cultivator which shall especially present the least obstructing surface to the impediments which it meets, and the least obstruction to the view of the attendant in watching and directing its movements, and to furnish the greatest strength and firmness with the least weight and cost; and it is in relation to these purposes that I desire its novelty and superiority to be considered.

I employ iron for the principal material, as combining the greatest strength and rigidity with the least bulk of any practicable material to attain the purposes; and this material is formed in bars or parts, comparatively thin and wide, and arranged in such a manner as to present the edges to the obstructions and to the sight of the operator. This form of the parts is also arranged in the matter of strength, so as to present the edges antagonistic to the greatest strain. A simple reference to the drawings will show how this part of the construction is disposed to effect the objects in view. The proportions of parts will be ascertained with sufficient accuracy by those of the drawings, according to any desired scale.

I will now proceed to describe more particularly those features requiring a precise specification.

To attain more effectually the purposes of strength and rigidity with small bulk and reduced cost, it is necessary to avoid as much as possible separable joints. I therefore weld together the thin bars A A B at the front end

a distance of eight inches, more or less, so that there can be no play or motion of one bar on the other, thereby enabling a greater height of construction, so as to pass above the ordinary obstructions of weeds, &c., and over rows of corn or other growing crop. The middle bar, B, is welded between the two side bars, A A, and turns downward, with a rounded shank, b, to receive its tooth D, near the front end of the whole cultivator. The two side bars, A A, extend backward considerably farther than the middle bar, and terminate in similar curved shanks, a a, for the reception of the teeth or shovels. These two outside bars are held and braced apart by a cross-bar, C, which is thin and wide, and placed nearly vertically edge-wise, so as to brace the whole width of the side bars, and also present but little obstruction to the view of the attendant. It is secured by two nuts, c c.

The handles H H are secured on the shanks of forked handle-braces G G, the parts g g of each being in one piece and bolted to the side bars, A A, at different points, substantially as shown, the forward one generally secured by the same nuts, c c, as secure the cross-bar C. These handle-braces may be adjustable, if desired, and in any case are as strong and rigid as well as light and unobstructing as can be. A stretcher-rod, I, connects the two shanks above the forks. The handles H H are generally made of wood.

The teeth, mold-boards, or shovels D D D may be of any desired shape, and they are respectively attached to their shanks, each by a single bolt, d, passing back through both the tooth and shank, and secured by a nut, e, as shown in Fig. 2. The teeth are kept from turning by a projection or wart, f, on the rear side of each entering a hole in the shank, as represented in Figs. 3 and 4.

A chain-hook in the front end of the welded bar serves to draw the cultivator by; and a straight-sided pivot-link in the hook, as shown in Fig. 1, keeps the chain from unhooking.

I desire it to be understood that I do not claim welding parts together, nor composing the parts of any machine with thin flat bars of iron; nor do I claim mere proportions of parts; but in the invention as above described

What I claim as my invention, and desire to secure by Letters Patent, is—

The construction and arrangement of the bars A A and B, placed vertically edgewise, and welded together at their front ends and braced by a thin cross - bar, C, placed vertically edgewise, in combination with the forked handle-braces G G, each formed in one piece, in the manner and for the purposes herein specified.

The above is a true and full specification of my improved corn fluke or cultivator.

I. B. MAHON.
